UNITED STATES PATENT OFFICE

THEODORE F. NAUMANN, OF PAWTUCKET, RHODE ISLAND, ASSIGNOR TO SEEKONK
LACE COMPANY, A CORPORATION OF RHODE ISLAND

THREAD CUTTER

Application filed April 27, 1929. Serial No. 358,658.

My invention relates to machines for cutting the binding threads, bridge threads or floating threads upon textile fabrics.

The essential objects of my invention are 5 to provide means for regulating the heights of the blades relatively to the fabric operated upon, and to effect this end selectively; to insure a complete cutting of every floating thread encountered by the blades; to facilitate the propulsion and reciprocation of the 10 machine; to provide means for elevating the blades and for maintaining the same in elevated position while the machine is inactive; and to attain the above ends in a structure of 15 an extreme compactness and portability, facile to operate, and simple and inexpensive to construct.

To the above ends essentially my invention consists in such parts and in such combinations of parts as fall within the scope of 20 the appended claims.

In the accompanying drawings which form a part of this specification,

Figure 1 is a top plan view of my thread 25 cutting machine showing parts thereof broken away in various planes,

Figure 2, a partial section of the same on line 2—2 of Figure 1,

Figure 3, a side elevation of the same, par- 30 tially fragmentary,

Figure 4, a fragmentary section on line 4—4 of Figure 2,

Figure 5, a perspective view of one of the 35 blades and its guard attached to the end of a supporting arm,

Figure 6, a detailed view of one of the blades disassembled, and

Figures 7, 8 and 9, side elevations of the 40 parts shown in Figure 5 indicating the positions shown assumed by the guard during the various stages of the thread cutting operation.

Like reference characters indicate like parts throughout the views.

The framework of my device includes sub- 45 stantially oblong side walls or plates 12 connected at their upper corners by cross bars 14; and at points below the latter, by cross bars 15. Journaled upon laterally project- 50 ing studs 19 in the lower corners of the side

plates are wheels or rollers 20 extending slightly below the lower edges of the plates. The described frame is longitudinally reciprocated, in this instance manually, by a detachable handle pivotally engaging one or 55 the other of the cross bars 14. The handle comprises a shaft 22, a handlebar 23 near its outer end, and a fork comprising diverging flat metal arms 24 fixed to the inner end of the shaft and provided with open upwardly 60 directed slots 26 near their inner extremities to loosely receive the cross bar.

Pivoted to each of the rods 15 is a brush frame comprising two interspaced flat metallic arms 28. The pivoted end of each arm 65 is formed by an open loop 30 closed by a bolt 32 connecting the free end 34 of the loop with the rod through perforations not shown. The arms have downwardly bent end portions fixed by screws 36 to the outer face of 70 a cross piece or brush back 37 in which are fixed downwardly directed tufts of bristles 38. The arms 28 are detachable, in cases where a brush is not required, by removing the bolts 32.

A pivot shaft 40 has its ends fixed in the side walls 12, midway their ends in a plane below the cross bars 15. It is provided at its ends adjacent the walls with spacing collars 43 at both sides of two oppositely disposed series of depending downwardly inclined blade carrying arms 48 and 49 respectively, loosely pivoted upon the shaft. The individual arms of one series alternate with the individual arms of the other series, and the arms of both series are alike in detailed 75 construction.

In detail each of arms 48 and 49 comprises an inner section 50 and outer section 51. At the inner end of each arm section 50 is an 80 opening 53 through which loosely passes the shaft 40. Surrounding the opening, in this instance, are spacing hubs 54 upon both sides of the section. Continuous with the inner ends of the arm sections 50 are longitudinally directed extensions or fingers 56. The outer end of the section 50 is curved and, as shown in Figure 4, is provided with a lateral circular recessed or counterstuck portion 58. The inner end of each outer arm section 51 85

is also curved and provided with a lateral circularly recessed or countersunk portion 60 abutting against the portion 58 of the arm section 50. The arm portions 58 and 60 are each provided with a central threaded perforation 62 registering with each other through which passes the threaded shank 64 of a clamping screw 65 having a head 66. By means of this screw the arm sections 50 and 51 may be angularly adjusted relatively to each other.

Carried by the outer end of each arm 51 is a flat substantially acute angular blade 68 having a horizontally disposed blunt bearing edge 69 upon the lower margin with a slight upward bevel or inclination 70 at its free end or point. The upper margin of the blade has a cutting edge 71 upwardly inclined from the blade point to a notched portion 72, near its inner end, also provided with a cutting edge 73, and a shoulder portion 74 adjacent the notched portion provided with a vertical cutting edge 75 continuous with the other cutting edges. The blade has an upwardly inclined attaching lug 76 at its inner end provided with an opening 77, and fits in an inclined lateral recess 78 in the outer end of the arm section 51, and is retained therein by a clamping screw 79 passing through the opening 77.

Cooperating with each blade is a forwardly directed resilient presser arm represented in a general way by the reference numeral 80 formed from a thin strip of resilient material. The inner end 81 of the strip constitutes an attaching portion resting upon the upper edge of the arm section 51, near its free end, and is fixed thereto by a screw 82 passing through a perforation, not shown. The remainder of the strip forms a horizontally disposed substantially elliptical arm comprising an arched upper portion 84, a curved end portion 85, and an arcuate lower portion 86 whose detached free end 87 is upwardly inclined and terminates adjacent the arm section 51. A central longitudinal slot 89 in the portions 85, 86 and 87 of the presser arm receives the cutting portion of the blade, so that the bifurcated portions of the presser arm slidably embrace the sides of the blade at points even below the cutting edge of the latter.

The blade carrying arms 48 and 49 are individually supported at their outer ends by the bearing edges 69 of the blades which slide, under the influence of gravity, in contact with the fabric 90 to be treated, which is clamped in any convenient manner to a floor, table, platform, or the like 91.

Means for maintaining the blades in elevated or inoperative position when the machine is not in operation consists of two similar oblong cooperating plates 93, extending across the machine transversely diverging from each other in a downward direction.

Each plate has inwardly directed rectangularly disposed attaching lugs 95 upon its ends adjacent its upper lateral edge provided with holes 97 through which the shaft 40 loosely passes. In this case the plates are assisted in maintaining a normally transversely inclined or distended position by retractile springs 98 attached at their inner ends, as at 99, to portions of the plates adjacent their lower lateral edges, and attached at their opposite ends to the rods 14. This form of spring means is not exclusive, and may be entirely dispensed with if desired. When the tensioning means are employed stop pins 100 in the end walls projecting into contact with the plates may be used. The plates are compressible to parallel vertical positions, as shown in Figure 3, by a rigid clamping yoke 102 whose legs 103, as the yoke is depressed over the plates, cause the lower lateral edges of the latter to move in an arc against the free end portions 56 of the arms 48 and 49 which tilt the latter and elevate the blades 68 into inoperative position.

To utilize the machine the operator applies the handle to either of the rods 14 and pushes or reciprocates the machine in any preferred direction over the fabric 90 supported with its superfluous threads exposed. The positions of the machine parts during operation are as shown in Figures 1 and 2. The blades 68 slide upon their bearing edges 69 over the fabric 90 operating to sever the loops, binding threads, bridge threads, or floating threads previously elevated more or less by the brush elements 38 positioned in advance of the blades. The cutting action of a blade upon a typical thread 104 is graphically shown in the last three figures of the drawings.

In Figure 7, the thread loop 104 has reached in its travel the presser arm portion 85 without severance, although often the severance has already occurred. In Figure 8 the unusually tough thread 104 has reached a point where it is increasingly pressed against the blade edge 71 by the presser arm portion 86 which has been forced upwardly by the thread. This pressure would naturally sever any thread. Assuming the latter to survive, however, it reaches finally the position shown in Figure 9 against the vertical cutting edge 75, where severance is invariable, and prevents tearing of the textile fabric 90 which otherwise would result.

I claim:

1. A portable self-contained apparatus for cutting bridge threads, embodying a frame mounted for longitudinal reciprocation comprising sides and cross bars, a pivot shaft supported in the sides, nonfrictional means for supporting the sides, a plurality of forwardly directed arms upon the shaft, rearwardly directed arms upon the shaft, and lon-

itudinally disposed upright cutting blades fixed to the ends of all the arms.

2. A self-contained apparatus for cutting bridge threads, a frame adapted to be longitudinally reciprocated comprising sides and cross bars, wheels supporting the sides, a shaft fixed at its ends in intermediate portions of the sides, forwardly directed depending arms pivotally engaged at their inner ends to the shaft, rearwardly directed depending arms pivotally engaged at their inner ends to the shaft, the several forwardly directed arms alternating with the several rearwardly directed arms, and longitudinally disposed upright cutting blades supporting the outer ends of all the arms.

3. In an apparatus for cutting bridge threads, a frame adapted to be longitudinally reciprocated, wheels supporting the frame, a transverse pivot shaft carried by the frame, arms comprising sections attached at their inner ends to the shaft, and sections pivotally connected at their inner ends to the outer ends of the first sections, and longitudinally disposed upright cutting blades upon the outer ends of the second sections.

4. In an apparatus for cutting bridge threads, a frame adapted to be longitudinally reciprocated, supporting wheels for the frame, a shaft fixed in the frame transversely thereof, a plurality of longitudinally disposed arms comprising inner sections provided with openings through which the shaft loosely passes, and outer sections overlapping the free ends of the inner sections, clamping screws connecting the overlapping ends of both sections, and longitudinally disposed upright cutting blades upon the outer end of the outer sections.

5. In an apparatus for cutting bridge threads, a frame adapted to be longitudinally reciprocated, a transversely disposed pivot shaft supported in the frame, longitudinally disposed arms engaged at their inner ends with the shaft, and blades attached at their inner ends to the outer ends of the arms comprising horizontal blunt bearing edges upon their lower margins and upwardly inclined at their outer ends, inwardly directed upwardly inclined cutting edges upon their upper margins, and vertical cutting edges upon their upper margins at the inner ends of the inclined portions.

6. An apparatus for cutting bridge threads, embodying a frame comprising sides and cross bars, a transverse pivot shaft mounted in intermediate portions of the sides, non-frictional means for supporting the sides, a plurality of parallel arms attached at their inner ends to the shaft and provided in their outer ends with lateral recesses, cutting blades, attaching lugs integral with the inner ends of the blades provided with openings and seated in the recesses, and screws in the arms passing through the openings

7. An apparatus for cutting bridge threads, a frame adapted to be longitudinally reciprocated comprising sides and cross bars, and a transverse shaft in the sides, a series of arms mounted at their inner ends upon the shaft, upright longitudinally disposed blades upon the outer ends of the arms provided along their upper margins with inclined cutting edges, and yielding means carried by the arms for pressing threads downwardly against the cutting edge of the blades.

8. In an apparatus for cutting bridge threads, a frame, a transverse pivot shaft mounted in the frame, supporting wheels upon the frame, a plurality of forwardly directed blade carrying arms mounted upon the shaft, blades upon the free ends of the arms comprising blunt bearing edges upon their lower margins and inclined cutting edges upon their upper margins, and curved resilient presser arms supported at their ends by the first arms and provided with longitudinally disposed slots into which the cutting edges are received.

9. In an apparatus for cutting bridge threads, sides, cross bars in the upper portions of the sides, a transverse pivot shaft in the walls centrally thereof in a plane below the cross bars, wheels pivotally attached to the lower corners of the sides, series of longitudinally disposed arms supported at their inner ends by the shaft, cutting blades fixed upon the outer ends of the shaft, longitudinally disposed arms pivotally supported at their inner ends to the cross bars, a cross piece fixed to the outer ends of the last mentioned arms in advance of the blades and downwardly directed bristles in the cross piece.

10. In an apparatus for cutting bridge threads, sides, cross bars in the upper portions of the sides, a transverse pivot shaft in the walls centrally thereof below the cross bars, wheels upon the lower portions of the sides, series of longitudinally disposed arms pivoted at their inner ends upon the shaft, cutting blades upon the outer ends of the arms, and a handle shaft provided with an open upwardly directed slot near its inner end adapted to loosely receive one of the cross bars.

11. In an apparatus for cutting bridge threads, a frame, wheels supporting the frame, a fixed shaft in an intermediate portion of the frame disposed transversely thereof, series of oppositely directed longitudinally disposed arms normally downwardly inclined outwardly loosely pivoted at their inner ends upon the shaft, longitudinal extensions upon the inner ends of the arms, the extensions of one arm series diverging relatively to the corresponding extensions of the other arm series, two oblong cooperating plates above the shaft normally parallel with each other and with the shaft and transversely diverging from each other in a down-

ward direction, attaching lugs upon the ends of the plates provided with holes through which the shaft loosely passes, and a clamping yoke downwardly slideable upon the plates to force the plates into depressing contact with the extensions of the arms.

12. A portable self-contained apparatus for cutting bridge threads, comprising a frame, means for longitudinally reciprocating the same, a pivot shaft carried by the frame transversely thereof, wheels supporting said frame, radially movable arms attached at their inner ends to the said shaft, and cutting blades fixed to the outer ends of said arms.

13. A portable self-contained apparatus for cutting bridge threads, embodying a frame, a pivot shaft carried by the frame, arms attached at their inner ends to the said shaft, means for longitudinally reciprocating said frame, and cutting means attached to the other ends of said arms and supporting the free ends thereof.

In testimony whereof I have affixed my
25 signature.

THEODORE F. NAUMANN.
